UNITED STATES PATENT OFFICE.

EDWARD E. GOLD, OF NEW YORK, N. Y.

STEAM-RADIATOR.

SPECIFICATION forming part of Letters Patent No. 508,134, dated November 7, 1893.

Application filed April 10, 1893. Serial No. 469,668. (No model.)

To all whom it may concern:

Be it known that I, EDWARD E. GOLD, a citizen of the United States, residing in the city, county, and State of New York, have invented certain new and useful Improvements 5 in Steam-Radiators, of which the following is a specification.

This invention relates to steam radiators, for use principally in the heating of railway 10 cars. It provides certain improvements in the construction of such radiators, the nature of which will be hereinafter set forth.

Figure 1 of the accompanying drawings is a horizontal section of a railway car illustrating 15 the new way of piping which is made admissible by the use of my improved radiator. Fig. 2 is a vertical transverse section thereof. Fig. 3 is a vertical longitudinal section thereof. Figs. 4 and 5 are respectively transverse 20 and longitudinal sections of my improved radiator. Figs. 6 and 7 are similar sections illustrating another construction thereof. Figs. 8 and 9 are similar views showing a further construction. Figs. 10 and 11 are similar 25 views illustrating another modified construction. Fig. 12 is a cross-section of a further modification.

Referring to Figs. 1, 2 and 3, let A designate the main steam-pipe beneath the car, from 30 which branch pipes a a extend into the car and communicate with branch steam-pipes B B entering one end of the heat storage radiators C C.

The radiators are extended in approximately 35 horizontal direction, being preferably inclined sufficiently to drain toward one end, and the pipes B B enter them at this end close to the top. At the same end close to the bottom, drainage pipes D D lead from the radiators, and being united pass down through 40 the floor of the car and terminate in automatic traps E E for discharging the water of condensation as it cools or as the pressure is removed. In the employment of such storage 45 radiators as heretofore used on railway cars, it has been most customary to introduce steam at one end of the radiator casing, and drain off the condensed water at the opposite end. This necessitates, when the connections 50 are made at the middle of the car, that

either the steam or drainage pipe shall extend alongside of the radiator to the remote end thereof, thereby employing considerable pipe, and involving other disadvantages of inconvenience and expense such as are well 55 understood. It is one object of my invention to provide such an internal construction of radiator as shall remove the necessity or advantage which has heretofore led to such system of piping. Other constructions of radiators have heretofore been provided by which both connections might be made at the same end, but they have been subject to practical disadvantages which it is the aim of my invention to overcome, such for example as the 60 trapping of a body of air within the radiator in such manner that the introduction of steam fails to expel the air.

One construction of my improved radiator is shown in Figs. 4 and 5. Like all storage 70 heaters, this radiator is constructed with an outer casing or shell F, and an inner heat storage body G. The shell F is an elongated tubular shell, preferably constructed as a piece of boiler tube having heads f f' fastened on its opposite ends preferably by screwing them into the heads. The steam inlet pipe B and drainage pipe D are both screwed into the head f. The heat storage body G may be either a vessel containing 80 liquid or it may be a solid body. In the construction here shown it is a solid body consisting of brick or unglazed earthenware, or terra cotta, or some other equivalent material, which is divided into sections placed 85 close together within the shell. The heat storage body conforms generally in shape to the interior of the shell, being partly in contact therewith, and partly out of contact therewith by being formed with grooves or 90 depressions b b. Along the top of each brick or section is formed a groove or channel c for providing a space or passage for steam entering the radiator, while along its bottom by preference is formed a groove or channel 95 d for permitting the water of condensation forming within the radiator to flow toward the outlet pipe D. The steam channel c is in line with the steam inlet pipe B, so that the steam is directed in a jet into and through 100

the channel c , whereby it is conducted to the opposite end of the radiator. The steam pipe B , or some other pipe or nozzle forming a continuation of it, should extend into the channel c sufficiently far to insure that the jet of steam introduced shall all enter the channel. Preferably this pipe is continued for a considerable distance within the radiator, either as an integral pipe or as a separate pipe, the latter construction, which is preferred, being shown in Fig. 5, where the separate pipe is lettered H . Some means is necessarily provided for preventing displacement of the bricks or sections in order that their channels c shall remain in line and constitute one continuous channel or steam conduit. The pipe H forms a convenient and effective means for accomplishing this purpose by simply extending sufficiently far to overlap the last brick or section, as shown in Fig. 5. The bricks are kept out of contact with the opposite heads of the shell by projections i therein, or any other suitable stops, so that chambers or empty spaces h are formed in the opposite ends of the radiator. Assuming the radiator to be full of air, the turning on of steam will throw a jet of steam through the pipe H and channel c to the opposite or farther end of the radiator, where the steam will enter the chamber h' and will flow thence back through the channels b toward the end from which it entered. In so doing it drives the contained air before it, and causes the air to pass out through the drainage pipe D , escaping at the trap E . As soon as the hot steam begins to pass out through the trap, the latter, being a thermostatic trap, is expanded by the heat and closes. The radiator is then filled with steam, by which it is quickly heated up and begins at once to radiate heat to the apartment. In so doing the steam is condensed, and the water of condensation collects in the spaces at the lower side of the radiator, chiefly in the channel d . As the radiator is tilted slightly, descending toward the drainage pipe D , the water of condensation flows out through this pipe, and as it cools the trap E opens and discharges it from time to time. When the heat storage body G is of brick or other porous material, a considerable quantity of the condensed water is taken into it by absorption. In any case the heat storage body G is heated by the steam, and after the steam is shut off the heat thus stored up is radiated to maintain the warmth of the apartment.

In the construction of radiators it is necessary to provide against the possibility of the bursting of any part by the freezing of condensed water which may remain in the radiator. By the combination of my radiator with a thermostatic trap E , the water condensing within the radiator drains off as fast as it cools. By the necessary inclination of the radiator with the end f downward, the steam pipes B and H are so inclined as to hold

some water of condensation within them, but the amount thus accumulating will not be sufficient to fill the pipe and consequently if it freezes will not burst the pipe.

70

Figs. 6 and 7 show a somewhat different construction wherein the steam pipe B enters the center of the tubular shell of the radiator, terminating in a short pipe or nozzle H' which projects into a central bore or channel c' formed through the bricks or sections of the solid body G' . This body is formed with longitudinal grooves b' at intervals around its exterior to constitute spaces for steam and condensed water. On turning on steam, the jet or current of steam flows from the nozzle H' through the bore or channel c' to the chamber h' at the opposite end, expelling the air therefrom and returning through the channels b' , driving the air ahead of it. Any of the condensation water which may form in the bore or channel c' will flow out through the space l beneath the nozzle H' .

Figs. 8 and 9 show a construction of storage heater wherein the heat storage body, here lettered G^2 , is a sealed vessel containing water or other suitable liquid adapted for the storage of heat, brine being preferable because of its cheapness and low freezing point. This inner vessel is so shaped as to form at the top between it and the outer casing, a steam space or channel c^2 , and at the bottom a condensation water space or channel d^2 , while the heads ff' are so constructed as to hold the inner vessel out of contact with them to form empty spaces or chambers h at the ends. The steam pipe B enters the upper side of the head f and discharges the jet of steam into the space or passage c^2 . The steam is prevented from flowing downward into the chamber h by means of a partition k formed on the inner side of the head f , which serves the double purpose of acting to confine the steam and force it to enter the channel c^2 , and as a stop for holding the vessel G^2 out of contact with the head f . On turning on steam it flows through the passage c^2 to the farther end of the radiator, descending through the chamber h' and flowing back in the contrary direction through the channel d^2 beneath and out through the drainage pipe D , forcing the air before it.

In Figs. 10 and 11 is shown a construction wherein the heat storage body, here lettered G^3 , is a vessel containing water which accumulates from the condensation of the steam. Within the outer casing F is placed the inner vessel G^3 , which is constructed of a tube closed at its opposite ends by heads and having holes m formed at its sides near the top for the double purpose of admitting steam into the vessel G^3 , so that this steam by condensing shall accumulate and keep replenished the body of water which is to serve as the heat storing medium, and of draining out any excess of this water in order that there shall be maintained a sufficient air space to provide

120

130

for the expansion of the body of water in freezing and prevent bursting the vessel. This specific construction of storage heater is not original with me. To this heater as thus far described I add according to my present invention, a steam-pipe H^3 extending through its upper part from end to end. This pipe is directly in line with the steam inlet pipe B, and to connect them the latter is prolonged within the casing to form a nozzle H^2 , which however might consist of a separate length or thimble of pipe. This nozzle H^2 enters loosely within the pipe H^3 , so that the entering steam shall be injected into this pipe and caused to flow through it to the chamber h' at the opposite end of the radiator. To provide for the expansion of the pipe H^3 as it is suddenly heated by the steam, its ends are made a loose fit with the ends or heads of the vessel G^3 . The heat storage vessel G^3 is raised up by blocks p in order to form beneath and around it a steam and condensed water space q . The steam on entering the chamber h' flows back through this space and expels the air, which is driven out through the drainage pipe D as before.

Fig. 12 shows another construction of storage heater in which the heat storage body, here lettered G^4 , is a closed or sealed vessel containing brine or other liquid. In this construction the upper part of the vessel is caved longitudinally to form a steam space or channel, here lettered c^4 , and which is in line with the steam inlet pipe B, the position of which is shown in dotted lines. The channel c^4 confines the steam and forces it to flow to the opposite end of the radiator, in order thereby to efficiently expel the air upon the turning on of steam. The inner vessel is held up by blocks p to form a steam space q around it as in the last described construction.

My invention may be otherwise altered in matters of detail without departing from its essential features, since the specific construction of such storage radiators is susceptible of very great modification. Those features of my invention which I consider essential are hereinafter defined in the claims.

I claim as my invention the following-defined novel features, substantially as hereinbefore specified, namely:

1. A heat storage radiator comprising a nearly horizontal elongated tubular outer shell inclined sufficiently to drain toward one end, having steam inlet and drainage openings both at the lower end of the shell, the drainage opening at the bottom and the inlet opening above it, a heat storage body inclosed in said shell, constructed to form a steam conduit communicating with said inlet opening and extending to the opposite end of the shell, and to form a space or channel for water of condensation along the bottom communicating with said drainage opening, whereby the entering steam is conducted to the farther

end of the radiator through said conduit, and the water of condensation flows back beneath to said drainage opening.

2. A heat-storage radiator comprising a nearly horizontal elongated tubular outer shell inclined sufficiently to drain toward one end, having steam inlet and drainage openings both at the lower end of the shell, the drainage opening at the bottom and the inlet opening at the top, a heat-storage body inclosed in said shell, the two constructed to form a steam conduit between them along the top of the radiator, extending from the inlet opening to the opposite end of the shell, and to form a space or channel for water of condensation along the bottom communicating with said drainage opening, and a steam inlet pipe entering the shell at said inlet opening and in line with said steam conduit to discharge steam thereinto, whereby the entering steam is conducted at the top to the farther end of the radiator through said conduit, and the water of condensation flows back beneath to said drainage opening.

3. A heat storage radiator comprising an elongated tubular shell, an inclosed solid heat-storage body, formed in sections, with a steam-space or channel along the upper side of each section, a steam inlet pipe entering the end of the shell near the top and extending within the shell in the channels in said sections, whereby said sections are retained in position with their channels in line, and the steam is conducted to the farther end of the radiator, and a drainage pipe for condensed water connecting with the same end of the shell near the bottom.

4. The combination of a radiator having a shell extended nearly horizontally, but inclined sufficiently to drain toward one end, and constructed with steam inlet and drainage openings both at the lower end, the former above and the latter beneath, and with an interior steam conduit extending from the steam inlet opening to the opposite end of the shell, whereby entering steam is conducted to the remote end of the radiator, and an interior passage or space for collecting water of condensation, returning along the lower side of the shell to the drainage opening, a steam-pipe extending to said steam-inlet opening, and a drainage pipe extending from said drainage opening to a trap or discharge.

5. The combination on a railway car, of two radiators having shells extended approximately horizontally along the side of the car, and formed with steam inlet and drainage openings in the adjacent ends of said shells, the inlet opening above and the drainage opening beneath, and said radiators inclined to drain toward the middle of the car, and constructed each with an internal steam passage extending from the steam inlet to the opposite end of the radiator, and with an interior space or passage for collecting water

of condensation, returning along the lower side of the shell to the drainage opening, with a steam-pipe having branches extending to the steam-inlet openings of both radiators, 5 and a drainage pipe leading from the drainage openings of both radiators and extending down through the car floor to a trap or discharge.

In witness whereof I have hereunto signed my name in the presence of two subscribing to witnesses.

EDWARD E. GOLD.
